DESCRIPTION

U.S. PATENT DOCUMENTS

FIG. 1 is perspective view of a flower-style air freshener assembly embodying the present invention on an enlarged scale;

D346,207 S * 4/1994 Martin
D379,651 S * 6/1997 Rondeau
D379,652 S * 6/1997 Okamoto
D380,821 S * 7/1997 Chen
D381,444 S * 7/1997 Yuen
5,725,152 A * 3/1998 Akyu
D395,529 S * 6/1998 Yuen
D422,350 S * 4/2000 Wu

FIG. 2 is a front view of the assembly;

FIG. 3 is a rear view of the assembly;

FIG. 4 is a left side view of the assembly;

FIG. 5 is a right side view of the assembly;

FIG. 6 is a top view of the assembly; and,

FIG. 7 is a bottom view of the assembly.
